(57) **CLAIM**

The ornamental design for a guillotine for cutting paper, as shown and described.

DESCRIPTION

FIG. 1 is a top, front and side perspective view of a guillotine for cutting paper showing our new design;

FIG. 2 is another top perspective thereof taken from the rear and side opposite;

FIG. 3 is a top perspective view thereof;

FIG. 4 is a bottom perspective view thereof;

FIG. 5 is a side perspective view thereof;

FIG. 6 is another side perspective view thereof, taken from the side opposite that shown in FIG. 5;

FIG. 7 is a front perspective view thereof; and,

FIG. 8 is a bottom perspective view thereof.
